(57) **CLAIM**

The ornamental design for a pair of disposable sanitary foot pads, as shown and described.

DESCRIPTION

FIG. 1 is a top perspective view of a pair of disposable sanitary foot pads showing my new design;

FIG. 2 is a top side view thereof;

FIG. 3 is a right side view thereof;

FIG. 4 is a bottom side view thereof;

FIG. 5 is a left side view thereof;

FIG. 6 is a front side view thereof;

FIG. 7 is a rear side view thereof; and,

FIG. 8 is a top perspective in use view shown in an alternate configuration with one tab bent.

The broken lines illustrating a foot in FIG. 8 are for the purpose of illustrating environmental subject matter and form no part of the claim.
